MANIFOLDING DEVICE

John E. Rohn, Rockville Centre, N. Y., assignor
to Autographic Register Company, Hoboken,
N. J., a corporation of New Jersey

Application March 12, 1932, Serial No. 598,343

1 Claim. (Cl. 282—1)

This invention relates to manifolding machines, and, as illustrated herein, is applied to an autographic register, although it is equally applicable to typewriting machines of the flat platen type.

In some lines of work it has often been desired to have writing produced on under copies without having it appear on the top or original worksheet or strip, and in order to do this the top 10 worksheet strip was made narrower than the under strips, or it was made as wide and provided with a longitudinal line of weakness along which the portion of the strip having the unwanted information could be removed.

These methods of accomplishing the purpose had inherent disadvantages, among which was the common disadvantage that the main portion of the bill or form was restricted in width, or the under-forms were made oversize, and thus required 15 larger and more cumbersome machines to handle them.

An object of the present invention is to so arrange that writing may be performed on the under strips through the upper strip by means 20 of a stylus or the like, and to this end the present invention provides a guide over the platen, on the margin frame in an autographic register, so that the person making the entries will know where to do so. When this is done, the upper 25 strip may have printed matter appearing in the space which would otherwise be occupied by indicia-receiving spaces on the under strips.

So that the marks of the stylus, or pencil if it is used, will not reach the upper worksheet, there is, 30 according to the present invention, placed under the guide and over the top record strip an impression-transmitting writing surface.

Other features and advantages will hereinafter appear.

40 In the accompanying drawings—

Figure 1 is a top plan view of an autographic register, partly in section, showing a writing guide embodied therein.

Fig. 2 is a plan view of the original or top worksheet strip.

Fig. 3 is a view of one of the under strips, of which there may be two or more.

Fig. 4 is a similar view of another worksheet strip, showing the duplicate express receipt and collection coupon which contain the information not wanted on the original or invoice.

Fig. 5 is a plan view of a portion of the platen in a flat platen typewriting machine, showing a writing guide applied thereto.

55 Fig. 6 shows a top plan view of this invention

having a cloth beneath the writing guide so that the writing may be performed with a lead pencil without marking the original copy.

As shown in the accompanying drawings, the autographic register has a platen 10 over which 5 worksheet strips 11, 12 and 13 pass and on which they are written upon. Interposed between the worksheet strips are carbon strips 14. At the delivery end of the register there are feeding disks 15 by means of which the strips are advanced 10 until apertures 16 in the strips are entered by the disks, whereupon advancement ceases and the strips are brought into registration.

The register, as usual, has a marginal frame 17 which holds the strips to the platen in super- 15 posed writing position, leaving an opening 18 through which writing is performed.

The worksheet strips 11, 12 and 13 are, as usual, printed and for example together constitute a combined invoice, express receipt, and way- 20 bill. The uppermost or original worksheet 11 has the usual heading 19 and space for customer's name and address 20 along with a main body 21 ruled and including designated spaces to receive a bill of the goods and for other kinds of infor- 25 mation desired. The body 21 is reproduced on both the duplicate strip 12 and the triplicate strip 13. However, above and below the body 21, the three strips are different. The upper part of the strip 13 is provided with an express re- 30 ceipt form 22 containing designated writing spaces conforming with the customer's name and address, etc. like those provided on the strip 11 so that the writing performed on the strip 11 will be reproduced in the proper place on the strip 13. 35

It is also provided at the right-hand side with a coupon 23 containing a date space, designated space for the number of pieces, weight, C. O. D., return charges, and declared value, which it is not desired to have appear on the original or invoice 40 strip 11. The express receipt 22 and coupon 23 are divided from the main portion 21 of the form on the strip 13 by transverse lines of perforations 24 and the express receipt 22 is divided from the coupon 23 by a vertical line of perforations 25. 45 When the form on the strip 13 is severed along the line 24, the portion 21 is used as a packing slip while the portions 22 and 23 are taken by the express company.

The strip 12 is a duplicate of the strip 13 50 except that the horizontal and vertical lines of perforations 24 and 25 are omitted and it constitutes the shipping record retained by the shipper, being a complete and integral record of the packing slip, the express receipt, and the express 55

receipt coupon which are designated 22a and 23a.

The space on the original strip 11 above the coupons 23 and 23a which are on the strips 13 5 and 12 may be occupied by any desired printing such as an advertisement or notice to the customer.

The delineated spaces on the coupons 23 and 23a are, however, not visible through the original 10 strip 11, and accordingly the user would not know where to make the entries. Since it is not desired to have this information appear on the invoice or original copy, it was heretofore necessary to make the invoice narrower than the 15 original and duplicate express receipts or to provide a vertical line of perforations along which the invoice could be torn to remove the undesired information. This involved not only a waste of paper but also cut down the available 20 space for the bodies 21 of the forms and made it necessary to spend time and effort in removing the part of the invoice strip.

This is avoided by providing the marginal frame 17 with a shield 26 having openings 27, 25 27a, etc., through which the operator may apply a stylus or other small instrument so that the desired information will appear on the strips 12 and 13 and yet not appear on the strip 11. As shown, the opening 27 is for the day and month 30 of the year, the opening 27a is for the year, the opening 27b is for the number of pieces; the opening 27c is for the weight; the number 27d is for the C. O. D., return charges, and the opening 27e is for the declared value. Of course, the 35 arrangement and number of openings 27, 27a, et cetera, shown herein are only by way of example, and, while the shield 26 is placed in the upper right-hand corner where it is less likely to interfere with the filling out of the form, it 40 should be understood that it may be located any-

where else desired or convenient, according to the make-up of the forms.

In applying the invention to a typewriter, such as an Elliott-Fisher flat platen typewriter, the writing guide or shield 26 may, as shown in Fig. 5 5, be mounted on the platen wherever desired.

According to the present invention, as shown in Fig. 6, the plate 26 is provided on its underside with a sheet of cloth 28 so that writing may be performed in the openings 27, 27a, et cetera. 10 With this arrangement it is not necessary for the user to lay down the pencil which he uses to fill in the main body of the form and pick up a stylus to write in the openings of the plate 26, and he may use his pencil for making the 15 notations in the openings 27, 27a, et cetera. The cloth 28 may be of a tracing cloth or similar thereto.

Other variations and modifications may be made within the scope of this invention and 20 portions of the improvements may be used without others.

Having thus described the invention, what is claimed as new and for which it is desired to obtain Letters Patent, is:—

In a manifolding machine, a platen whereupon worksheet strips with interleaved transfer material are supported for writing operations; a plate supported over the platen having designated writing openings for indicating to the operator the location of invisible designated indicia-receiving spaces on the under strips so that writing may be performed thereon through the medium of said transfer material with a pencil or the like; and an impression transmitting writing surface directly under and carried by the plate to prevent writing performed in said designated spaces from appearing on the uppermost strip.

JOHN E. ROHN. 40
